UNITED STATES PATENT OFFICE.

VICTOR ST. CLAIR BLACKETT, OF MONCTON, NEW BRUNSWICK, CANADA.

TRACK-SUPPORTING DEVICE.

Application filed November 24, 1924. Serial No. 752,002.

To all whom it may concern:

Be it known that I, VICTOR ST. CLAIR BLACKETT, a citizen of Canada, and a resident of Moncton, New Brunswick, in the 5 Dominion of Canada, have invented a new and Improved Track-Supporting Device, of which the following is a description.

My invention relates to a track supporting device and particularly to a device for temporarily supporting the track under conditions requiring the temporary removal of a part of the track or the customary support for the track, for the purpose of laying a pipe culvert, for example.

15 The general object of my invention is to provide a track supporting device of the indicated character so formed and arranged as to be readily applied to the track to bridge the temporary excavation and 20 adapted to afford ample support for the portion of the track to which the device is applied.

More specifically, the invention has in view the provision of a temporary track 25 support made up largely of track rails and which may be assembled and disassembled with facility and dispatch.

30 The nature of my invention and its distinguishing features and advantages will more clearly appear as the description proceeds.

Reference is to be had to the accompanying drawings forming a part of this specification, it being understood that the drawings are merely illustrative of one example 35 of the invention.

Figure 1 is a plan view of a section of a railway track having my supporting device emplaced therein;

Figure 2 is a side elevation;

40 Figure 3 is an enlarged transverse section in a plane indicated by the line 3—3, Figure 1;

Figure 4 is an enlarged detail in side elevation.

45 In Figure 1 are shown railway ties 10 and track rails 11 on said ties. The numeral 12, Figure 2, indicates an excavation beneath the track rails and ties, thus leaving a portion of the track unsupported.

50 In accordance with my invention I provide a series of compound girders, each girders made up of two or more track rails 13. One of the compound girders is laid at each side of each track rail 11, the emplaced 55 girders at each rail thus embodying at least two track rails at each side of each main rail.

Each girder composed of the girder rails 13, embodies spacers or separators 14 having a longitudinal bore through which a bolt 15 is passed, said bolts receiving nuts 115 thereby completing the girder and holding the rails 60 13 thereof rigidly in parallel relation.

Hangers 16 are provided and advantageously these are each in the form of a short section of an inverted track rail, the hangers 65 being disposed between the rails 13 of a girder and having the flanges 17 of the hanger rail resting on the adjacent base flanges of said girder rails 13.

The hangers 16 at the opposite sides of each track rail 11 jointly receive beams 18 which thus extend transversely beneath the track rails 11 with their ends beneath the girders. The ends 19 of each beam 18 extend through holes 20 in the hangers 16 and 70 the beams are held against displacement by any suitable means such as keys 21 and cotters 22, for example. In practice the girder rails 13 are not higher than the track rails 11, thus making certain that no part of the 75 track supporting device extends above the plane of the tops of the track rails to constitute an obstruction to moving trains. This is especially important when the track supporting device is emplaced in a main line 80 track. However, there may be instances in which the stated precaution may be unnecessary as for example, when the supporting device is used in sidings. The use of track rails in the forming of girders is with a view 85 to practical considerations and it will be understood that the cross section of the 90 girder rails may be varied. It will be clear from the foregoing that the supporting device may be emplaced and removed without 95 disturbing the relative positions of the track rails and track ties. The use of the device also does away with the necessity of providing trestlework when an excavation is 100 made beneath a railway track, the trestlework as is well known offering an obstruction 105 to the work to be done beneath the track. As in the illustrated example, the under part of the supporting device, that is, the beams 18 and hangers 16, are within the planes of the ties and therefore offer no obstruction to the work to be done in the excavation. When the supporting device is in use as shown, it will be readily seen that the train load is transferred from the track 110 rails 11 to the beams 18 directly underneath, thence to the hangers 16 and to the

- girder rails 13. The girder rails are made of a length to bridge the unsupported length of the track and the ends of the rails rest on the track ties remote from the excavation.
- 5 By providing at least two rails 13 to each girder, the total number of girder rails plus the track rails provides at least 10 rails instead of two to take up the load over the unsupported length of track.
- 10 I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.
- Having thus described my invention, I claim:
- 20 1. A track supporting device including a pair of girders adapted to be disposed lengthwise at opposite sides of a track rail, each girder including a plurality of rails and means tying the rails into rigid relation to 45 constitute the girder, together with a beam adapted to be disposed transversely beneath

a track rail and extending to the girders of the pair, and means supporting said beam from said pair of girders.

2. A track supporting device including a 30 pair of girders adapted to be disposed lengthwise at opposite sides of a track rail, each girder including a plurality of rails, and means tying the rails into rigid relation to 35 constitute the girder, hangers having flanges resting on the flanges of the girder rails, and a beam extending transversely from girder to girder at the under side thereof and having their ends supported in said hangers.

3. A track supporter including a pair of girders adapted to be disposed lengthwise at opposite sides of a track rail, said girders including each a plurality of rails, spacers between the rails and transverse bolts holding 40 said rails in rigid relation; together with hangers having support on the flanges of the girder rails, and a transverse beam at the under side of the girder rails and supported by said hangers.

VICTOR ST. CLAIR BLACKETT.
